UNITED STATES PATENT OFFICE.

ROBERT A. GALLY, OF CINCINNATI, OHIO, ASSIGNOR TO THE BALDWIN COMPANY, OF CINCINNATI, OHIO.

MUSIC-PLAYER-PNEUMATIC COUNTERWEIGHT.

1,264,631.

Specification of Letters Patent. Patented Apr. 30, 1918.

Application filed August 14, 1917. Serial No. 186,226.

To all whom it may concern:

Be it known that I, ROBERT A. GALLY, a citizen of the United States, and residing at Cincinnati, in the county of Hamilton 5 and State of Ohio, have invented certain new and useful Improvements in Music-Player-Pneumatic Counterweights, of which the following is a specification.

In applicant's prior Patent #891,801, 10 June 23, 1898, is shown and claimed an extended heel lever striker pneumatic, preferably adapted to cause the heel lever to always be held in contact with the abstract which it was to operate. In some instances, 15 where the material or any horizontal downward stroke pneumatic 1 is rather stiff, or where there is an extra heavy abstract or sticker 2 or other parts co-acting with the heel lever 3 or other lever of the pneumatic 20 1, as shown herein and in applicant's other application #184,355, filed Aug. 3, 1917, and #184,677, filed Aug. 6, 1917, and #185,161, filed Aug. 8, 1917, it is desirable to use a counterweight 4 to partly or wholly overcome 25 or exceed any stiffness of the covering material of the striker pneumatic 1 or the weight of any sticker 2 or other part as nut 5 bearing down on the heel lever extension 3, such counterweight 4 being of such size, 30 and at such position on the pneumatic 1 forward of its hinge 6, as to give the most desirable balance of weight for satisfactory actuation of such striker pneumatic 1.

It is to be understood that this counterweight feature may be used with any horizontal down stroke pneumatic, either in upright or grand pianos, and whether for overcoming the stiffness of the covering material of such pneumatic, or against the 40 weight of any levers, heel levers, stickers, or other parts that tend to open the pneumatic by raising its moving board.

The drawing herewith is of a side view of a piano keyboard and keybed with the 45 present invention shown as placed under the keys and keybed, but it is to be understood that such counterweighted pneumatics may be used either above or below the keys, and for either grand or other pianos, or in any 50 part of a pneumatic musical apparatus where they may be desirable, and be subject to:—

What I claim as my invention, which is:—

1. A horizontal striker pneumatic having 55 a moving board at its upper side, the said

board being downwardly movable at one end thereof and hinged at its other end; a member actuated by and connected to the said moving board and whose weight constantly acts to raise the said moving board; and a weight attached to the said moving board at a distance from the hinged end thereof.

2. A horizontal striker pneumatic having a moving board at its upper side, the said board being downwardly movable at one end thereof and hinged at its other end; an arm fixed with the said board and extended beyond its hinged end; and a weight attached to the said moving board at a distance from the hinged end thereof. 70

3. A horizontal striker pneumatic having a moving board at its upper side, the said board being downwardly movable at one end thereof and hinged at its other end; an arm fixed with the said board and extended beyond its hinged end; an actuating means resting on the extended part of the said lever, and a weight attached to the said moving board at a distance from the hinged end thereof. 80

4. A horizontal striker pneumatic having a moving board at its upper side, the said board being downwardly movable at one end thereof and hinged at its other end; an arm fixed with the said board and extended beyond its hinged end; a vertical sticker resting on the extended part of the said lever; and a weight attached to the said moving board at a distance from the hinged end thereof. 90

5. A horizontal striker pneumatic having a moving board at its upper side, the said board being downwardly movable at one end thereof and hinged at its other end; a weight attached to the said moving board at a distance from the hinged end thereof; and an intermittent air service connected to said pneumatic to cause the downward movement of the said board. 95

6. A horizontal striker pneumatic having a moving board at its upper side, the said board being downwardly movable at one end thereof and hinged at its other end; a weight attached to the said moving board at a distance from the hinged end thereof; and an intermittent air service connected to said pneumatic to cause the downward movement of the said board which is assisted by the said weight. 100

7. A horizontal striker pneumatic having 110

a moving board at its upper side, the said board being downwardly movable at one end thereof and hinged at its other end; a weight attached to the said moving board at a distance from the hinged end thereof; and an intermittent suction air service connected to said pneumatic to cause the downward movement of the said board.

8. A horizontal striker pneumatic having
10 a moving board at its upper side, the said board being downwardly movable at one end

thereof and hinged at its other end; a weight attached to the said moving board at a distance from the hinged end thereof; and an intermittent suction air service connected to 15 said pneumatic to cause the downward movement of the said board which is assisted by the said weight.

ROBT. A. GALLY.
